(57) CLAIM

The ornamental design for a carton for use with a cleansing composition or article, as shown and described.

DESCRIPTION

FIG. 1 is a front perspective view of a design for a carton for use with a cleansing composition or article;

FIG. 2 is a front view of the design for a carton of FIG. 1; FIG. 3 is a right side view of the design for a carton of FIG. 1;

FIG. 8 is a front perspective view of a second embodiment for a carton for use with a cleansing composition or article; FIG. 9 is a front view of the design for a carton of FIG. 8; FIG. 10 is a right side view of the design for a carton of FIG. 8;

FIG. 11 is a rear view of the design for a carton of FIG. 8; FIG. 12 is a left side view of the design for a carton of FIG. 8;

FIG. 13 is a top view of the design for a carton of FIG. 8; and,

FIG. 14 is a bottom view of the design for a carton of FIG. 8.

In the drawings, the broken line showing portions of a carton depicts environment and forms no part of the claim.

1 Claim, 6 Drawing Sheets
